UNITED STATES PATENT OFFICE.

N. GREENARD DU BOIS, OF BROOKLYN, NEW YORK, ASSIGNOR OF ONE-HALF TO F. R. MALONEY, OF SAME PLACE.

RAILROAD-SWITCH.

SPECIFICATION forming part of Letters Patent No. 330,826, dated November 17, 1885.

Application filed September 8, 1884. Serial No. 142,519. (No model.)

To all whom it may concern:

Be it known that I, N. GREENARD DU BOIS, a citizen of the United States, residing at Brooklyn, in the county of Kings and State 5 of New York, have invented certain new and useful Improvements in Railroad-Switches; and I do hereby declare the following to be a full, clear, and exact description of the invention, such as will enable others skilled in 10 the art to which it appertains to make and use the same.

The invention relates to that class of devices in which the switch is operated by the movement of the street-car. The object is to 15 provide the track and car with such devices that the driver can control the switch at pleasure.

My invention therefore consists of constructions and combinations, all as will hereinafter 20 be described in the specification, and pointed out in the claims, reference being had to the accompanying drawings, in which—

Figure 1 represents a plan view of the track, having one section of the rail removed to show 25 the switch-working parts beneath; Fig. 2, a section on line xx , Fig. 1; Fig. 3, a plan of the bottom of the car; Fig. 4, a longitudinal section of a portion of the car; and Fig. 5 a section on line yy , Fig. 3. Fig. 6 represents 30 a top plan of the crank and pawl.

In Fig. 1 the main track is shown with two branch or side tracks; but it will be obvious from the following description that the device can be used on a single branch. It will therefore be only necessary to minutely describe one branch, as both are constructed in a similar manner, the necessary changes for a right or left hand branch track being made.

A represents the main track; A' and A'' , the 40 right and left hand branch tracks. One section-rail of the main track A, at a point near the switch, is provided with a grooved rail, a , which at the switch end a' is made flaring to connect it with the branch. Upon end a' is 45 a raised part, a'' , having a semicircular end, a'' , against which the movable tongue-rail or switch a'' abuts. Against the opposite end, a'' , the end of the flange on the main-track rail a and the inner flange of the branch-track rail 50 a'' abut for an obvious purpose. The other rail is provided with a stationary tongue-rail,

a^8 , which abuts against the flange of the branch-track rail a , to serve as a bearing for the car-wheels when the car is shifted from the main to the branch track by movable tongue-rail 55 a^4 . If two branches are desired, the end a' of each main-track rail is provided with a movable tongue-rail, a^4 , and a stationary rail, a^8 , as shown in Fig. 1. The movable tongue-rail a^4 is provided on its under side with a projection, a^{10} , which passes downwardly through an opening, a^{12} , in the groove of the rail. The projection a^{10} is of the same length as the opening a^{12} , which is provided with an extension, a^{14} , of less width than the opening a^{12} . The 60 toe a^{13} of projection a^{10} projects beneath the rail to hold the loose end of the tongue down. The tongue may be withdrawn from opening a^{12} by removing the pivot a^{11} . Beneath the rail a is a box, a^{15} , having bearings a^{16} for 70 a shaft, a^{17} , provided with collars a^{18} , a^{19} , and a^{20} . The collar a^{18} has a longitudinal groove, a^{21} , for the projection a^{10} on the movable tongue-rail a^4 , which is moved to the right or left as the shaft a^{17} is partly revolved to the 75 right or left, thus causing the car to pass either on the main or the branch track.

To partly revolve shaft a^{17} various means may be used, that shown, however, being preferred, and which will now be described. 80 Upon shaft a^{17} , as before mentioned, are double collars a^{19} and a^{20} , each having longitudinal grooves a^{22} and a^{23} , the latter being on the opposite side of the shaft to the former. Between each pair of collars is a groove, a^{24} , for 85 the reception of posts a^{25} and a^{26} , having trunnions a^{27} , which rest in the grooves a^{22} and a^{23} . These posts a^{25} and a^{26} project through openings a^{28} on opposite sides of the groove in the rails a , and are alternately raised above the 90 level of the track, while their lower ends alternately rest on the bottom of socket-stops a^{29} .

It is obvious that many different forms of device may be used to depress the posts to the level of the track and operate the switch. If 95 such a device could be manipulated by the driver, manifest advantages over the usual manual method would be gained. The device shown in Figs. 3, 4, and 5 accomplish this result, and the parts of which I will now describe.

B represents the bottom of a street-car, and

C the wheels. Attached to the under side of bottom B is a plate, b, having pendants b', to which cross-bars b² are attached. These bars have semicircular depressions for the axle c. 5 Between these bars b² is a space, b³, through which the tongues b⁴ of a tread, b⁵, project and extend upwardly through openings b⁶ in plate b, which serves as a guide for the same. The tread is preferably semicircular in form, and 10 when not in use fits closely to the semicircular part of bars b².

B' and B² are crank-levers, one at each end of plate b, and having their inner ends projecting toward each other and resting upon a lug, b⁷, on tongue b⁴, and when moved downwardly force the tongue and tread downwardly. When the downward pressure upon tongues b⁴ is removed, springs b⁸ force them back to the former position. In the plan view strap-springs are shown; but it is obvious that compression-springs may be substituted therefor by inserting them between the lugs b⁷ and bars b².

To operate the crank-levers B' and B² various means may be used, one manner being shown in the drawings, and consists of a drum, D, journaled to one end of the car, and having a crank, D', provided with notches d, for the double pawl d', which holds the drum 25 in the desired position by inserting one of its ends in one of the notches. Between the flanges of the drum is a post, d², passing through and holding the chain d³ in place. One end of this chain is connected by link d⁴ to the end b⁹ of lever B', and by links d⁵ with end b¹⁰ of lever B². When the crank D' is turned in the direction indicated by arrow 1, the lever B' is operated, and when turned in the direction of arrow 2 lever B² is operated. So far the description relates to a single-horse car; but it is obvious that by placing a similar device at each end of a two-horse car the device can be operated from either end.

The operation of the device is as follows: 45 Suppose a car were moving on the main track in the direction of the arrow 3 and the driver wishes to pass to the right-hand branch track. He should turn the crank D' in the direction of arrow 2. The tread marked 4 would be 50 lowered and strike the right-hand post a²⁵, depress it to the surface of the track, and by reason of this movement partly revolve the shaft, which will shift the right-hand rail a⁴ from the position shown in dotted lines to the position 55 shown in full lines, Fig. 1, and thus close the main passage and connect the groove in rail a with the groove in the right-hand rail of the branch track. If it be desired to switch the next car to the left-hand branch, the crank D' 60 is moved in the direction of arrow 1, and the

tread marked 5 will be lowered to the track, ready to depress post a²⁵ on the left-hand side of the track, and thus shift the rail a⁴ on the left-hand track. Before this can be done the right-hand rail a⁴ must be shifted to the position shown in dotted lines, Fig. 1. This is automatically accomplished by the rim or tread of the car-wheel striking the right-hand post a²⁶, which revolves the shaft in an opposite direction to that caused by right-hand post a²⁵. If it be desired to send the second or another car on the main track, the rim or tread of the car-wheels will strike both posts a²⁶, if raised, and shift the rails a⁴ to the position shown in dotted lines, Fig. 1. If only a single branch 70 track is used, the car may be provided with a double-flange car-wheel, which will operate both posts on the rail nearest the branch track. When it is desired to go straight ahead, neither of the treads are lowered. The tread of the 80 car-wheels will strike the post a²⁶ on each side and shift the rails a⁴ into the recess.

What I claim as new is—

1. In a switch, the combination of a movable-tongue switch-rail having a projection, a shaft having a slot for said projection, and posts on each side of and connected with said shaft, one of said posts being operated by the car-wheel and the other under the control of the driver, substantially as described. 90

2. In a switch, the combination of a movable-tongue switch-rail having a projection, a shaft having a slot for said projection, and collars provided with longitudinal openings, and posts having trunnions resting in said 95 longitudinal slots and adapted to be alternately raised by the car-wheel and mechanism under control of the driver, substantially as described.

3. A car-switch having on the wheel-bearing flange of the main rail a post operated by the car-wheel, and a second post outside the wheel-bearings, and adapted to be operated by a device on the car under control of the driver, substantially as described. 100

4. A car-switch the main rails of which are grooved, the outer flanges having a depressible post, and the inner flanges having a depressible post which is raised when the posts upon the outer flanges are depressed, and depressed when the posts on the outer flanges are raised, substantially as and for the purpose set forth. 105

In testimony whereof I affix my signature in presence of two witnesses.

N. GREENARD DU BOIS.
